UNITED STATES PATENT OFFICE

2,012,316

ELECTROSURGICAL APPARATUS

Lawrence D. Miles, Schenectady, N. Y.

Application October 1, 1932, Serial No. 635,806

10 Claims. (Cl. 174—177)

My invention relates to electro-surgical apparatus and more particularly to such apparatus suitable for locating solid conductive bodies embedded in the flesh of animate beings.

5 It often happens that solid conductive, or metallic, bodies become embedded in the flesh of a patient. For example, in the use of hypodermic or other surgical needles, it sometimes happens that the needle breaks off within the flesh of the patient. Also in the case of certain 10 dental surgical operations, drills, needles or other objects, occasionally become embedded in the flesh. In case such a foreign body becomes embedded in the flesh adjacent to sinews or small 15 bones, it is exceedingly difficult to locate the body by means of an ordinary lance, both because the adjacent sinews or bones may have a resilience similar to that of the body embedded in the resilient flesh, and because of the fact that any 20 incisions made in an effort to locate the body immediately become filled with blood, so as to obscure the embedded body. In the past, it has been proposed to remove such embedded bodies by means of a very strong electro-magnet, but such a method has the inherent disadvantage 25 that it is limited to ferrous metals, and that, in the cases of relatively small bodies, such for example, as broken needles which are deeply embedded, it is not possible to secure a sufficient 30 pull to remove the body. One of the principal problems in removing such an embedded object is that of locating the object, after which any number of methods may be utilized for removing it.

35 It is an object of my invention, therefore, to provide a new and improved electro-surgical apparatus for locating solid conductive bodies embedded in the flesh of animate beings.

40 It is another object of my invention to provide a new and improved electro-surgical apparatus including an exploring electrode for locating solid conductive bodies embedded in the flesh of animate beings, in which a positive indication will be given when the exploring electrode contacts 45 with the embedded body.

45 It is another object of my invention to provide a new and improved surgical instrument which is particularly suitable for use in connection with my improved electro-surgical apparatus.

50 In accordance with my invention, an electrode, such, for example, as a flat metallic plate or band, is arranged to form a conductive connection with the flesh of a patient from whom it is desired to remove a solid conductive body, such

for example, as a metallic needle, drill, etc. There is also provided an exploring electrode preferably having a sharp point or cutting edge in order that its use may entail the minimum of incision of the patient's flesh. The exploring 5 electrode is preferably insulated except for a very restricted surface at the point, or cutting edge, of the electrode. The two electrodes are interconnected through a source of electric current and an indicating means is connected in 10 circuit with the electrodes and is adapted to respond to the contacting of the conductive surface of the exploring electrode and the embedded body.

For a better understanding of my invention, 15 together with other and further objects thereof, reference is had to the following description taken in connection with the accompanying drawing, and its scope will be pointed out in the appended claims. Referring to the drawing, Fig. 20 1 is a schematic diagram of an apparatus embodying my invention for locating a solid conductive body embedded in the flesh of a patient; Fig. 2 is an enlarged cross sectional view of the point of the exploring electrode of Fig. 1; Fig. 3 25 illustrates a modified form of an exploring electrode suitable for use in connection with my invention, while Fig. 4 is an enlarged cross sectional view of the exploring electrode of Fig. 3 taken along the line A—A.

30 Referring more particularly to Fig. 1 of the drawing, there is illustrated an electro-surgical apparatus embodying my invention for locating a solid conductive body, such as a portion of a metallic needle 10, in the flesh of a patient. 35 This apparatus includes a conductive electrode 11 suitable for contacting with some portion of the patient's body, as by encircling his arm, as illustrated, or by inserting in the mouth of the patient, in case the contact resistance of the arm 40 is too high. There is also provided an exploring electrode 12 provided with an exploring point or blade 13, a handle 14, and an electrical terminal 15 which makes an electrical connection with the point 13, and is preferably removable from 45 the handle 14. As illustrated in more detail in Fig. 2, the blade or exploring point 13 of the electrode 12 comprises a needle-like metallic member 16 covered with an insulating composition, such for example, as a baked enamel, which 50 extends almost to the tip of the electrode. The terminal 15 of the exploring electrode 12 is interconnected with the contact electrode 11 through a circuit including the terminal 17, the adjustable connection 18 of a voltage adjusting means,

such as a potentiometer 19, mechanical or thermionic relay means, such as the operating coil 21 of a mechanical relay 22, the terminal 23, an indicating device or meter 24, and terminals 25 and 26. The potentiometer 19 is connected across any suitable source of electric current, either direct or alternating, such as a battery 20. There may also be provided an indicating lamp 27 and an alarm device, such as a buzzer 28, energized through a circuit including the terminal 29, contacts 30 of the relay 22, the battery 20, an auxiliary source of electric current such as a battery 31, and the terminal 32. The apparatus comprising the potentiometer 19, the relay 22, 10 and the batteries 20 and 31 are preferably included in a container or box 33 having the outlet terminals 17, 23, 25, 26, 29 and 32, to which may be connected flexible conductors in circuit with the electrodes and the indicating means so that these 15 apparatus may be conveniently located near the operator.

The operation of the above described apparatus is as follows: If the point 13 of the exploring electrode 12 be inserted in the flesh of the patient, but not in contact with the embedded needle 10, the contact resistance of the uninsulated tip of the electrode 12 will be very high relative to the contact resistance of the electrode 11 or the resistance of the other elements included in the 20 circuit interconnecting the electrodes. The adjustable connection 18 should be moved to such a position that the relay 22 operates to close its contacts 30, thus energizing the signal lamp 27 or the alarm device 28, and then the connection 18 should be moved to lower the voltage impressed upon the electrode circuit until the relay 22 just opens its contacts to deenergize the signal lamp 27 or the alarm device 28, and a reading of the indicating meter 24 should be noted. The exploring electrode may be moved 25 in the neighborhood of the embedded needle 10, but no matter how close the uninsulated tip of the electrode 12 comes to the needle 10, so long as these two do not contact, the resistance of the electrode circuit will still be limited primarily by the contact resistance of the tip of the exploring electrode and no appreciable indication will be obtained, either by a change in the reading of the meter 24 or in the operation of the relay 22. 30 However, as soon as the uninsulated tip of the exploring electrode 12 contacts with the embedded needle 10, a direct metal to metal contact is established which has a very low resistance. The contact resistance of the exploring electrode now becomes that of the embedded needle or conductive object 10 which has a very much larger conductive surface than the exploring electrode 12, and accordingly a proportionately lower resistance. This lowering of the resistance of the electrode circuit causes an increase in current therein 35 which will be indicated on the meter 24. This increase in current will also be effective to energize the relay 22 to close its contacts 30 and thus complete the circuit for energizing the signal lamp 27 or the alarm device 28. Thus either a visible or an audible indication, or both, of the contacting of the exploring electrode 12 with the embedded metallic object 10 is given to the operator.

It will be apparent to those skilled in the art that, in case an indicating meter 24 is not desired, this may be omitted from the circuit, in which case the terminals 23 and 25 will be connected directly together. Similarly, it will be apparent 40 that either the indicating lamp 27 or the alarm

device 28 may be disconnected in case it is not desired, or in case neither is desired, they may be both omitted and the terminals 29 and 32 connected together, in which case an indication is obtained only by means of the meter 24. In case the signal lamp or alarm device are sufficiently sensitive to respond to the change in current in the electrode circuit, it will be apparent that the relay 22 may be omitted and the indicating devices 27 and 28 connected directly in the electrode circuit. It will also be apparent to those skilled in the art, that while I have illustrated my apparatus as energized from batteries 20 and 31, any other suitable source of either direct or alternating current of high or low frequency may be substituted therefor without departing from my invention. Also, in case the voltage of the battery 20 or other source of energy is sufficiently high, the auxiliary battery 31 may be omitted. 45

In Fig. 3 is illustrated another surgical instrument which may be used in place of the exploring electrode 12. The instrument or electrode 34 of Fig. 3 is essentially a surgical lance, comprising a handle portion 36 and a blade or cutting portion 35. The blade portion 35 of the lance 34 is insulated with any suitable insulating compound, such for example, as a baked enamel, but this insulation extends only up to the cutting edges leaving the actual cutting edges uninsulated, as is illustrated in more detail in Fig. 4, which represents a cross section of the blade 35 along the lines A—A. In Fig. 4 the metallic blade 37 is illustrated as being covered with an insulating compound 38 up to within a very short distance from the cutting edges 39 and 40. The handle 36 is provided with a suitable connection for the electrical terminal 15 of the arrangement of Fig. 1. In the use of the lance 34 of the Fig. 3, the contact resistance of the electrode circuit is limited by the contact resistance of the cutting edges of the lance, which is relatively high. When, however, either of these cutting edges contacts with the embedded body, the contact resistance of the exploring electrode circuit is reduced, as described above, and an indication is given by the meter 24 or the signal lamp 27, or alarm device 28, as desired. 50

While I have described what I at present consider the preferred embodiments of my invention, it will be obvious to those skilled in the art that various changes and modifications may be made without departing from my invention, and I, therefore, aim in the appended claims to cover all such changes and modifications as fall within the true spirit and scope of my invention. 55

What I claim as new and desire to secure by Letters Patent of the United States is:

1. Electro-surgical apparatus for locating solid conductive bodies embedded in the flesh of animate beings comprising an electrode for forming a low resistance conductive connection with said flesh, a separate exploring electrode including means for imparting thereto a high contact resistance, a source of electric current connected in circuit with said electrodes, and indicating means responsive to the contacting of said exploring electrode and the embedded body. 60

2. Electro-surgical apparatus for locating solid conductive bodies embedded in the flesh of animate beings comprising a relatively low contact-resistance electrode for forming a conductive connection with said flesh, a separate exploring electrode having means including a restricted conductive surface for imparting thereto a high contact resistance, a source of electric current 70

connected in circuit with said electrodes, and indicating means responsive to the contacting of the conductive surface of said exploring electrode and the embedded body.

5 3. Electro-surgical apparatus for locating metallic bodies embedded in the flesh of animate beings comprising an uninsulated metallic electrode for forming a low resistance conductive connection with said flesh, a separate insulated metallic 10 exploring electrode having a restricted uninsulated portion, a source of electric current connected in circuit with said electrodes, and indicating means responsive to the contacting of the uninsulated portion of said exploring electrode 15 and the embedded metallic body.

4. Electro-surgical apparatus for locating solid conductive bodies embedded in the flesh of animate beings comprising an electrode for forming a conductive connection with said flesh, a separate exploring electrode including means for imparting thereto a high contact resistance, a source of electric current connected in circuit with said electrodes, and current responsive 20 means connected in the circuit of said electrodes 25 and operable to give an indication of the contacting of said exploring electrode and the embedded body.

5. Electro-surgical apparatus for locating solid conductive bodies embedded in the flesh of animate beings comprising an electrode for forming a conductive connection with said flesh, a separate exploring electrode including means for imparting thereto a high contact resistance, a source of electric current connected in circuit 30 with said electrodes, a relay included in the circuit of said electrodes and operable in response to the contacting of said exploring electrode and the embedded body, and indicating means controlled by said relay.

40 6. Electro-surgical apparatus for locating solid conductive bodies embedded in the flesh of animate beings comprising an electrode for forming a conductive connection with said flesh, a separate exploring electrode including means for imparting thereto a high contact resistance, a source of electric current connected in circuit 45 with said electrodes, an auxiliary source of electric current, indicating means, and a relay included in the circuit of said electrodes and operable in response to the contacting of said exploring electrode and the embedded body to connect said indicating means in circuit with said auxiliary source of current.

7. Electro-surgical apparatus for locating solid conductive bodies embedded in the flesh of animate beings comprising an electrode for forming a low resistance conductive connection with said flesh, a separate exploring electrode including means for imparting thereto a high contact resistance, a source of electric current connected in circuit with said electrodes, an auxiliary source of electric current, indicating means, and a relay included in the circuit of said electrodes 10 and operable in response to the contacting of said exploring electrode and the embedded body to connect said indicating means in series with both of said sources of current.

8. Electro-surgical apparatus for locating solid conductive bodies embedded in the flesh of animate beings comprising an electrode for forming a low resistance conductive connection with said flesh, a separate exploring electrode including means for imparting thereto a high contact resistance, a source of electric current provided with voltage adjusting means, a circuit including said electrodes and said source of current, and indicating means responsive to the contacting of said exploring electrode and the embedded body. 15 20 25

9. Electro-surgical apparatus for locating solid conductive bodies embedded in the flesh of animate beings comprising an electrode for forming a low resistance conductive connection with said flesh, a separate exploring electrode including 30 means for imparting thereto a high resistance, a source of electric current, a potentiometer connected across said source, a circuit including said electrodes and said potentiometer, and indicating means responsive to the contacting of said 35 exploring electrode and the embedded body.

10. Electro-surgical apparatus for locating metallic bodies embedded in the flesh of animate beings comprising an uninsulated metallic electrode for forming a low resistance conductive 40 connection with said flesh, an insulated metallic exploring electrode having a restricted uninsulated portion, a source of current, a potentiometer connected across said source, said potentiometer being connected in circuit with said electrodes, an auxiliary source of electric current, indicating means, a relay included in the circuit of said electrodes and operable in response to the contacting of said exploring electrode and the embedded body to connect said indicating 45 50 means in circuit with said sources of current.

LAWRENCE D. MILES.
